UNITED STATES PATENT OFFICE

WILLY LEDIG, OF BERLIN, GERMANY, ASSIGNOR TO GENERAL ELECTRIC COMPANY,
A CORPORATION OF NEW YORK

WINDING HEAD FOR FILAMENT MOUNTING MACHINES

Application filed April 11, 1928, Serial No. 269,199, and in Germany May 3, 1927.

This invention relates to filament mounting machines such as disclosed in application for U. S. patent Serial No. 243,698, filed December 30, 1927 by Ledig and Loebe for a filament mounting machine, relating to a filament mounting machine for making stems for electric incandescent lamps, and in which a rotatable bending head for forming eyes or loops in the anchor serves at the same time to enclose the coiled filament in the anchor loops formed by the bending head. In that working position of the machine where the anchor loops are formed there are horizontally movable loop forming slides, corresponding in number to the bending heads, and actuated both by control levers from a control plate and also by hinged levers from the gear segments which rotate the bending heads.

The present invention has for its object to simplify the working parts essential for the formation of the anchor loops, which are usually very small, and at the same time avoid angles at the hinges of several hinged levers. To this end, and in accordance with the invention, each bending head has a vertically reciprocating slide actuated by the machine drive and acting at its upper end directly through a cam on the leaf spring which presses into engagement with the bending head the anchor wire in which a loop is being made. As soon as the reciprocating slide has risen far enough to apply the leaf spring to the anchor in which the loop is to be made it also acts through a lost motion connection to move the gear segment which rotates the bending heads for making the anchor loop.

Since both the application of the leaf spring for holding the anchor wire in the bending head, and also the rotation of the gear segment which directly drives the bending heads, are due to the very precisely controlled vertical movement of the slide, the loops on the anchor wires are formed with great accuracy and precision.

One example of an embodiment of the invention is shown in the accompanying drawings in which Fig. 1 is an elevation of a bending head of a filament mounting machine; Fig. 2 is a horizontal section along the line

2-2 of Fig. 1; Fig. 3 is a vertical section of the bending head along the line 3-3; Fig. 4 is an enlarged end view; Fig. 5 is an enlarged horizontal section of that part of the bending head shown in Figure 2; and Fig. 6 is a view of the lower end of a mount on which the filament has been mounted by the anchor bending head.

As in the filament mounting machine of the application above identified there is fixed in loop bending position on a table 57 of the machine a radially set standard 58 for each anchor wire 31 of the stem 6. Each standard 58 has an inwardly extending radial arm 59 on the inner end of which a loop bending head 60 is rotatably mounted on a stationary tubular spindle 61 and is held in place on the spindle by a bracket 62. Each bending head 60 has a longitudinal slot 63 in one side, and the stationary tubular spindle 61 has a corresponding longitudinal slot to permit the introduction of the coiled filament into the tubular spindle 61 from the top through the slot 63 of the bending head. Each bending head is rotated on the tubular spindle 61 by a pinion 64 which meshes with a gear segment 65. The end face of the rotatable bending head 60 has a ratchet tooth groove 83 of which the longitudinally projecting face forms a bending shoulder or lug for engaging the anchor wire 31 which rests on the end face of the head and is pressed into the groove or underneath the shoulder by a leaf spring or resilient finger 81 which extends across the end of the bending head.

Both the application of the leaf spring or resilient finger 81 and the rotation of the bending head 60 are, in accordance with the invention, controlled by the up and down movement of a reciprocating slide 113 guided vertically in the standard 58 and normally drawn down by a spring 114 until its collar 115 rests on the upper end of its guide 116 on the standard 58. The upper end of the slide 113 is bent to form a cam 117 overlying the leaf spring 81 as best shown in Fig. 3. Between the cam and the leaf spring 81 is a cam follower 118 pivoted on a pin 119 on a lug 120 on the standard 58. In the standard 58

beside the pin 119 is a set screw 121, which acts as a stop for the gear segment 65.

The gear segment is rocked on its pivot from the slide 113 through a lost motion connection which permits the slide to apply the spring 81 to the bending head before the bending head is rotated by the segment 65. In the particular arrangement illustrated the desired lost motion between the slide and the gear segment is obtained because the slide 113 has near the middle a longitudinal slot 122 through which extends an arm 123 of the gear segment 65. A spring 124 connected to this arm normally holds the gear segment 65 in contact with the set screw 121 and the bending head 60 in such a position that its slot 63 is at the top as shown in Figs. 1 and 4. With the slide 113 in its lowest or normal position the slot 122 is in such a position that there is considerable play or lost motion between the arm 123 and the lower end 125 of the slot which acts as a lug to engage the arm 123 and move the segment 65, but only after the slide has risen a certain distance.

As described more fully in the application above identified, when the stem is in the loop bending position the stem holding head of the machine is lowered from the position shown in dotted lines to that shown in full lines in Fig. 1 to introduce the coiled filament hanging from the leads 9 of the stem into the tubular spindles 61 of the bending heads 60 and at the same time place the ends of the anchor wires 31 across and on the projecting ends of the bending head spindles 61. As soon as the stem holder and stem have been lowered into the position shown in full lines in Fig. 1, the slides 113 on all the standards 58 begin to rise as the adjustable tappets 126 on the lower ends of the slides are encountered by the control plate 78 which is lifted by the driving mechanism, and therefore, the slides are pushed upwardly in spite of the springs 114. The cam 117 on the upper end of each slide 113 thereupon swings the cam follower 118 on its pivot and thereby presses the underlying leaf spring 81 against the anchor wire 31, forcing it into the ratchet tooth groove 83 of the bending head 60. In this way the anchor wire is held in the groove 83 and thus locked to the bending head. During this portion of the movement of the slide the bending head is stationary because of the lost motion between the slide and the arm 123.

Shortly after the spring 81 presses the anchor into the groove 83 the bottom or lower shoulder 125 of the slot 122 in the slide, acting as a lug or abutment, comes in contact with the arm 123 so that as the upward movement of the slide 113 continues gear segment 65 is carried along and swung about on its pivot. The upward movement of the slide thus causes a partial rotation of the gear segment 65 and a rotation of the bending head

60 and with the bending of the anchor wire 31 in the groove 83 into a loop about the coiled filament, which lies in the bore of the tubular spindle 61 of the bending head. As the slide 113 moves downward these movements occur in reverse order, the gear segment 65 together with the bending head 60 first returning to their initial position, after which the pressure of the leaf spring 81 on the anchor wire and the end face of the bending head is released. The removal of the coiled filament, now fastened to the anchors on the stem, is brought about by raising the stem holding head and thereby lifting the mounted filament out of the bending heads, as described in the above identified application.

What I claim as new and desire to secure by Letters Patent of the United States is:

1. In a machine of the character described, an anchor wire bending head comprising a tubular spindle having a longitudinal slot, a loop bender rotatable on said spindle and having a corresponding longitudinal slot, said bender having a driving pinion for rotating it and a radial ratchet tooth groove on its end face, a leaf spring fixed at one end with its free end overlapping the end face of said bender, an actuating slide mounted to reciprocate vertically and transversely of said spring, a cam on the upper end of said slide to engage said spring and press its free end against the end face of said loop bender, a pivoted gear in mesh with the pinion on said loop bender, and a lost motion connection between said slide and said gear to actuate said gear from said slide after said cam has engaged said spring.

2. In a machine of the character described, an anchor wire bending head comprising a tubular spindle having a longitudinal slot, a loop bender rotatable on said spindle and having a corresponding longitudinal slot, said bender having a driving pinion for rotating it and a radial ratchet tooth groove on its end face, a leaf spring fixed at one end with its free end overlapping the end face of said bender, an actuating slide mounted to reciprocate and having a cam for pressing the free end of said spring against the end face of said bender during the advance of said slide, and means actuated by said slide during its advance and while said spring is pressed against the end of said bender for rotating said bender.

3. In a filament mounting machine of the character described, an anchor wire bending head comprising a tubular spindle having a longitudinal slot, a loop bender rotatable on said spindle and having a corresponding longitudinal slot, said bender having in its face a radial ratchet tooth groove, a resilient member movable toward the end face of said loop bender to hold an anchor wire in said groove during rotation of said bend-

- er, a reciprocating actuating slide, and connections to said slide to move said member into contact with the end of said loop bender and subsequently rotate said loop bender 5 while maintaining said member in position adjoining said loop bender.
4. In a machine of the character described, an anchor wire bending head comprising a rotatable loop bender having a bending 10 groove in its end, an anchor holding member movable along the axis of said loop bender to adjoin its end, and an actuating member movable to hold said holding member adjoining the end of said loop bender during 15 most of its travel and to rotate said bender during a lesser portion of its travel and while said holding member adjoins the end face of said bender.
5. In a loop bending machine, the combination of a rotatably bender having an end face shaped to grip a wire laid radially of said bender and in contact with said face, a resilient finger movable axially of said bender to contact with said wire and hold it 20 against said face, and means for moving said finger into contact with said face and for rotating said bender while maintaining said finger in contact with the face of the bender.
6. In a loop bending machine, the combination of a rotatable bender having an end face with a projecting shoulder to engage a wire laid on said face radially of said bender, a resilient finger movable axially of 25 said bender to contact with said face, and means for moving said finger into contact with said face to hold said wire underneath said shoulder and for rotating said bender while maintaining said finger in contact with the face of the bender.
- 40 7. In a loop bender, the combination of a spindle, a bending head mounted to rotate on said spindle and having a face perpendicular to said spindle and through which the end of said spindle projects, said face being shaped to engage a wire lying in contact with said face and across the projecting end of said spindle and to bend said wire around said spindle as said head rotates, and means cooperating with said head to hold said wire in contact with said face during rotation of said head.
8. In a machine of the character described, the combination of a rotatable loop bender 45 having a face shaped to engage an anchor wire laid radially across said face, a finger movable into juxtaposition to said face to hold an anchor wire in engagement with said face during rotation of said loop bender to bend the anchor wire into a loop, an actuating slide mounted to reciprocate along an axis transverse to the axis of rotation of said loop bender, and connections between said loop bender, said finger, and said slide for maintaining 50 said finger in juxtaposition with said
- face of said loop bender and simultaneously rotating said loop bender.
9. In a machine of the character described, the combination of a rotatable loop bender having a driving pinion and a face shaped to 55 engage an anchor wire laid radially across said face, a finger movable into juxtaposition to said face to hold an anchor wire in engagement with said face during rotation of said loop bender to bend the anchor wire into a 60 loop, an actuating slide mounted to reciprocate along an axis transverse to the axis of rotation of said loop bender, a driving gear in mesh with said pinion, a connection between said slide and said driving gear to 65 rotate said driving gear as said slide reciprocates and thereby rotate said loop bender, and means actuated by said slide to control the position of said fingers during rotation of said loop bender.
10. In a machine of the character described the combination of a loop bender mounted to rotate about a horizontal axis and having a face shaped to engage an anchor wire laid 70 radially across said face, a finger cooperating with said face to hold the anchor wire in engagement with said face, a vertically movable slide adjacent said loop bender, driving means actuated by said slide during a 75 portion of its travel to rotate said loop bender, and finger controlling means actuated by said slide during a greater portion of its travel to hold said finger in juxtaposition to 80 said face of said bender.
11. In a machine of the character described the combination of a loop bender mounted to rotate about a horizontal axis and having a face shaped to engage an anchor wire laid 85 radially across said face, a finger cooperating with said face to hold the anchor wire in engagement with said face, a vertically movable slide adjacent said loop bender, a driving gear for said loop bender mounted in position to be engaged and rotated by said slide near the end of the upward travel of 90 said slide and thereby rotate said loop bender, and a cam on said slide to move said finger into position adjoining said face of said loop bender prior to the rotation of said driving gear and to maintain said finger in said position 95 during the remainder of the upward travel of said slide.
12. In a machine of the character described, the combination of a rotatable loop bender having a face shaped to engage a wire laid 100 across said face, a finger movable into juxtaposition to said face, and common actuating means for rotating said loop bender and maintaining said finger in place during rotation of said loop bender.
- In witness whereof, I have hereunto set my hand this 28th day of March, 1928.
- WILLY LEDIG.
